UNITED STATES PATENT OFFICE.

FRANK J. DURDA, OF WAELDER, TEXAS, ASSIGNOR OF ONE-HALF TO J. C. HOLLOWAY,
OF WAELDER, TEXAS.

COTTON-DRYING APPARATUS.

1,187,287.

Specification of Letters Patent. Patented June 13, 1916.

Application filed November 6, 1915. Serial No. 60,100

To all whom it may concern:

Be it known that I, FRANK J. DURDA, a citizen of the United States, residing at Waelder, in the county of Gonzales and State of Texas, have invented new and useful Improvements in Cotton-Drying Apparatus, of which the following is a specification.

My invention relates to an apparatus for drying cotton preliminary to the action of ginning the same, the object of the invention being to provide an apparatus whereby the cotton may be agitated and treated in a loosened or divided condition to the action of heat, by means of which it may be rapidly and thoroughly dried and placed in condition to be handled in a gin to better advantage.

A further object of the invention is to provide reliable and efficient means for feeding the cotton, loosening it up or subdividing it to a desired degree, maintaining it in a state of subdivision for a determined period, and subjecting it during such period and while in a state of transit to the action of currents of a drying medium, whereby the cotton will be rapidly and thoroughly dried.

The invention consists of the features of construction, combination and arrangement of parts herein fully described and claimed, reference being had to the accompanying drawings in which:—

Figure 1 is a diagrammatic view of a complete drying apparatus embodying my invention. Fig. 2 is a side elevation of the drier *per se*. Fig. 3 is an opposite side elevation of the same. Fig. 4 is a rear elevation of the drier. Fig. 5 is a vertical front to rear section through the same. Fig. 6 is a vertical transverse section.

In carrying my invention into practice, I provide a drier proper 1, of a construction hereinafter described, and to which extends a pipe 2 for conducting hot air thereto from a heating coil 3, which may be suitably disposed within a boiler or other furnace 4 and has an inlet end 5 leading externally of the furnace for the supply of fresh air thereto. A fan or blower 6 is disposed in the pipe 2 at a point between the drier and the heating coil for the purpose of sucking the heated air from the coil and forcing the same to the drier. Communicating with the pipe 2 at a point between the drier and fan is a vent pipe 7 having a controlling valve 8, and dis-

posed in the pipe 2 between the drier 1 and the pipe 7 is a controlling valve 9. The valve 9 is closed when the drier is not in action and is opened for the passage of the hot air to the drier when the latter is set 60 into action. By means of the pipe 7 any air which has been overheated prior to setting the drier into action may be exhausted on opening the valve 8, after which said valve is closed and the valve 9 opened to allow the 65 air heated to the proper degree to pass to the drier. A suction pipe 10 is provided for conveying the cotton from a wagon or other source to the drier and has arranged therein a suction and force fan 11 while an outlet pipe 12 is provided for the discharge of the dried cotton from the drier and communicates with a suction feed pipe or main 13 leading to the ginning apparatus 14, a valve 15 being arranged at the point of juncture 75 of the outlet pipe and main by means of which communication may be closed or established between the same at any time, as will be readily understood.

The drying apparatus 1 comprises a vertical oblong rectangular casing 15 provided with doors 16 and 17 at the front and rear thereof whereby access to the interior of the casing may be readily and conveniently obtained. Communicating with the upper 85 rear portion of this casing is a damp cotton inlet pipe 18 leading from the pipe 10, and in line with which are arranged spaced, horizontal slatted feed rolls 19 and 20 which are adapted to engage and feed the cotton 90 to a pair of rolls 21 and 22. The roll 21 is arranged at a point below with its axis on a line between the rolls 19 and 20, and said roll 21 is disposed in spaced relation to the roll 22, which is located forwardly 95 thereof, also in spaced relation to a rear concaved or toothed stationary divider 23. The rolls 21 and 22 are provided with teeth similar to the teeth of the stationary divider, and these teeth upon the respective elements 100 are arranged in staggered relation, the teeth upon the rolls being arranged to work between each other, while the teeth of the roll 21 work between the teeth of the stationary rear concave 23. These elements serve to divide up the amount of heavy compact cotton and to reduce it to divided or thin and fluffy state, thus placing it in proper condition to be better acted upon by the agitating and heating devices. The concave 105 110

23 is preferably detachably secured in position by suitable turn buttons or other fasteners 25 within an opening in the back wall of the casing so that it may be readily removed on the event of clogging of the feeders or for the substitution of another concave.

The material fed by the rolls 21 and 22 passes downward and forward in contact with underlying curved screens 26, which serve as guides to conduct the cotton to a front deflector 27 for delivery to the agitator, the said screens also serving to permit of the separation and discharge from the cotton of any dirt or foreign materials loosened therefrom by action of the feeding and dividing rolls. The cotton striking the deflector 27 passes downwardly and rearwardly over a series of inclined trays 28 having screen bottoms, said trays extending alternately in opposite directions and providing a zigzag path or course of travel for the loosened cotton which is under treatment, the said trays being supported by an openwork oblong rectangular frame 29.

In the operation of the drier the frame 29 is vibrated back and forth, thus causing the cotton to feed down the shelves through the force of gravity and that produced by the vibration of the frame, the dust and other fine foreign particles which may separate from the cotton being discharged successively through the screens and finally falling upon an imperforate shelf 30, down which the refuse matter slides by gravity into the bottom of the casing or outward through an opening therein.

The means for supporting and vibrating the frame 29 comprises resilient or spring metal hangers 31 connecting the frame at or adjacent to its corners to the frame of the casing 1, which latter is preferably of openwork construction so as to permit vapors to escape and facilitate the drying action. The spring hangers 31 permit back and forth vibration of the screen frame through the medium of an actuating mechanism comprising a stub shaft 32 having at one end cranks 33 and 34, said shaft being journaled upon the casing and having its crank member 33 coupled by a connecting rod 35 to one of the upper hangers 31 and having its other crank member 34 connected by a link 36 with one arm of a bell crank lever 37, the other arm of which is coupled by a connecting rod 38 to one of the lower hangers, the construction being such that as the shaft revolves the connecting rods will be reciprocated and swing or vibrate the screen frame back and forth in an obvious manner. The cotton on its course of travel is subjected to the drying action of a heated fluid, such as hot air, which fluid is injected through injector pipes 39 disposed beneath the various screens 26 and 28, said pipes

having outlet slots or perforations 40 arranged at such an angle as to inject the blast of air from below upward through the adjacent screen in the direction of travel of the cotton, by means of which all portions 70 of the cotton will be permeated by the air, the moisture driven out and the cotton dried. The dried cotton discharges from the base of the casing through a suction outlet 41 communicating with the delivery pipe 12. 75

The means for operating the various parts of the apparatus consist of intermeshing gears 42 and 43 on the shafts of the feed rolls 19 and 20, which gear 43 meshes with a worm 44 on a suitably journaled 80 shaft carrying a gear 45 having a plurality of annular sets of teeth arranged concentric with and at different distances from its axis.

The gear 45 is arranged to mesh with a 85 gear 46 loose upon the shaft 21' of the feed roll 21, said gear 46 having a sleeve 47 carrying a set screw 48, whereby it may be fixed to the shaft 21' and is adjustable for engagement with any one of the annular 90 sets of teeth on the gear 45, whereby the picking rolls 21 and 22 and the drying and screening mechanism may be driven at different rates of speed. As shown, the shaft 21' of the roll 21, which is driven as described from the shaft of the feeder 20, carries a pulley 48 connected with pulleys 48^a and 48^b on the shaft of the roll 22 and the shaft 32, respectively, by a belt 48^c, by means of which the roll 22 and shaft 32 are 100 driven. On the shaft 19' of the feeder 19 is a pulley 49 for driving said shaft from any suitable source of power. The means for supplying hot air from the pipe 2 leading from the heater 3, to the pipes 39 consists of a series of pipes 50 arranged upon the side of the screen frame opposite the screen frame vibrating mechanism and which may consist of one or more jointed sections, as indicated at 51, to permit the 110 frame to vibrate without interference from the pipe connections, while at the same time permitting of the free supply of hot air or other heating medium to the internal blast pipes. 115

I claim:—

1. In an apparatus for drying cotton, the combination of a frame or casing, feeding means for conducting the cotton thereto, means for dividing up or loosening the 120 feeding cotton, a series of inclined perforated shelves arranged in zigzag order within said frame or casing, and over which the cotton is adapted to travel between the top and bottom of the casing, means for heating the interior of the frame or casing, and means for vibrating the inclined shelves.

2. In a machine for drying cotton, the combination of a frame or casing, means for feeding the cotton thereto, spurred rolls ar- 125

5 ranged to engage and loosen up the fed cotton, a conductor arranged in the path of the loose cotton and having a series of inclined shelves arranged in zigzag order, means for
vibrating the conductor to constantly turn the cotton over and over in its course of transit, and means for passing a heating fluid through said shelves.

10 3. In an apparatus for drying cotton, the combination of a frame or casing, feeding means for conducting the cotton thereto, means supported upon the frame or casing for dividing up or loosening the feeding cotton, a vibratory frame arranged within

the casing and having inclined shelves ar- 15 ranged in zigzag order over which the cotton is adapted to pass, means for vibrating said frame, and conducting pipes for a heating fluid arranged below the shelves and having outlets for directing the currents 20 of heated fluid through the shelves against the feeding cotton.

In testimony whereof I affix my signature in presence of two witnesses.

FRANK J. DURDA.
